UNITED STATES PATENT OFFICE

FREDERICK S. HAAS, OF CINCINNATI, OHIO, ASSIGNOR TO CINCINNATI GRINDERS INCORPORATED, OF CINCINNATI, OHIO, A CORPORATION OF OHIO

GRINDING MACHINERY

Application filed August 5, 1927. Serial No. 210,836.

This invention relates to improvements in grinding machinery and has particular reference to the control mechanism therefor.

One of the principal objects of the present invention is the provision of an improved combined pedal and manual control mechanism for the several movements of a grinding machine.

A further object of the present invention is the provision of a control mechanism satisfactorily operable to control either the several movements of parts necessary for transverse grinding or to control the lesser movements employed in connection with the 15 plunge cut method of grinding.

Another object of the present invention is the provision of a control mechanism by which the movements of both table and work may be simultaneously controlled or the 20 actuation of one of said parts adjusted without disturbance of the other.

Other objects and advantages of the present invention should be readily apparent by reference to the following specification taken 25 in conjunction with the accompanying drawing, and it will be understood that any modifications may be made within the scope of the appended claims, without departing from or exceeding the spirit of the invention.

30 Figure 1 is a front elevation of a machine embodying these improvements.

Figure 2 is a diagrammatic view illustrating the operation of the several control mechanisms, and

35 Figure 3 is a corresponding view illustrating a shifting of certain of the parts, the complete circuit not being included.

In the drawing the numeral 10 designates 40 the bed of a conventional type grinder having mounted thereon the bearings 11 for the grinding wheel 12 and the reciprocable table 13 for the work. Said table 13 is provided with a footstock 14 for engagement with one end of the work piece 15 and with a headstock 16. The table further bears a suitable motor 17 coupled with the headstock for actuation thereof. The table may be shifted on 45 the bed in any suitable manner as for example through the use of a feed screw 18 rotatable by a gear 19 which may be coupled

with the screw through clutch mechanism 20. It will of course be understood that any mechanical equivalent of these parts such as an hydraulic table shifting mechanism and control valve for actuation thereof could be substituted for the feed screw and clutch mechanism so long as a control device for table movement is employed, and same is deemed within the purview of the invention and claims.

To control the movement of the table there is pivoted to bed 10 the table control lever 21 carried by the rock shaft 22. This shaft has secured thereon the shifter arm 23 for actuation of clutch 20 and has an additional arm 24 to which is pivoted link 25. This link at its lower end has an elongated slot 26 receiving pin 27 on shifter arm 28. Shifter arm 28 is in turn carried by rock shaft 29 which supports the treadle 30 having the 60 pedal portions 31 and 32 at opposite sides of the shaft, whereby the treadle may be selectively rocked in either direction as desired. Coupled with this treadle as by attachment to shaft 29 is the switch actuating plate 33 which supports the switch plunger 34 or 35. 65

These plungers serve to actuate in opposite directions the switch blade control 36 as will be readily understood by reference to Figure 2. When the plunger 34 is raised as shown in this figure the control circuit 37 for solenoid 38 is closed. This in turn acts on switch 39 of line circuit 40 for motor 17 causing actuation of the motor which therefore starts the work rotation. On the other hand, when the pedal 31 is depressed raising plunger 35 this swings switch member 36 to open the control circuit and deenergize the solenoid. In this event spring 41 opens motor line switch 39 stopping the motor and thus discontinuing rotation of the work.

The advantageous operation of the present structure should be readily apparent by reference to the several illustrations of position of the parts in the different views of the drawing. When the work is not being operated upon as for example in setting up of the machine, changing of work pieces or the like, the control lever 21 and treadle 30

- are in the position shown in Figure 1, in which event the clutch 20 is disengaged so that there is no feed of the table and line 40 is open so that there is no rotation of the work. Pin 27 then occupies an intermediate position in slot 26, the treadle also being in an intermediate or non-tilted position. As lever 21 is shifted to the left or starting position the end of slot 26 will engage with pin 10 27 rocking the treadle into the position indicated in Figure 3. Consequently, both the table clutch or actuating mechanism will be rendered operative and also the power line for the headstock motor energized. Thus the 15 single motion of the lever 21 toward the left or starting position serves to initiate movement of both the table and the headstock. Subsequently, if it is desired to stop the movement of the table without interfering with 20 movement of the work this may be effected by swinging handle 21 to the right or stopped position. However, if it is desired to stop the entire machine treadle 30 is rocked by pressure on pedal 31 shifting plunger 35 to 25 break the circuit controlled by switch member 36 deenergizing the headstock motor and at the same time disengaging clutch 20.

These operations all enter into the control of the machine when used for ordinary or 30 traverse grinding.

In addition, when the machine is utilized for what is known as plunge cut grinding in which the table movement is not utilized, the lever 21 may be left in its right hand position and the starting and stopping of the work controlled solely by pressure on pedal parts 31 and 32 respectively, pin 27 in this instance riding idly in slot 26 which is of sufficient length to permit the desired movement without shifting of the lever 21.

I claim:—

1. A grinding machine, including a bed, a table member movable on the bed, a rotary work driving member, power means for shifting the table, a motor for driving the work driving member, a control lever for the table power means, a control switch for the motor, and connections between the lever and switch whereby the switch may be actuated jointly 45 with or independently of the movement of the lever.

2. A grinding machine or the like, including a bed, a table movable on the bed, a rotatable work driving member, power actuated means for shifting the table, additional means for rotating the work driving member, a control lever for one of said means, a control pedal for the other of said means, and a connection between said lever and said 55 pedal having a lost motion provision whereby the parts may be given certain jointly actuated control movements and certain independent control movements.

3. In a grinding machine or the like, the 60 combination with a bed, of a table movable

on the bed, an oscillatable control lever for said table movement, a rotatable work engaging device, electrical means for rotating the device, a control switch therefor, a pedal for operating the switch, and a linkage connection between the lever and pedal, including a lost motion coupling whereby the lever may be moved into stopping position without effecting the switch.

4. A machine of the nature disclosed, including a bed, a table movable upon the bed, a drier for the table, a rotatable work engaging device, means for rotating said device, an oscillatable control lever for starting and stopping the table movement, a second shiftable member for controlling the rotation of the work engaging member, and a slotted link connection between said control devices whereby movement of the lever in one direction will operate both the table and work drive mechanisms and movement in the opposite direction will disconnect the table drive without effecting the work drive.

5. A machine of the character described, including a bed, a table movable on the bed, a work rotating member, a drive motor for the work rotating member, a pedal control for starting and stopping the motor, driving means coupleable with the table for actuation thereof; a manual control for the connection and disconnection of the drive with the table; and a connection having a lost motion provision between the pedal and manual control permitting independent actuation of the pedal when the manual control is in stopped position, said connection including interengaging portions rendered operative by movement of the manual control into starting position, whereby the motor will be simultaneously actuated and stopping movement of the pedal will correspondingly actuate the manual table control device.

6. A grinding machine of the character described, including a bed, a table mounted for reciprocation on the bed, a feed screw for actuation of the table, a drive gear loosely mounted on the screw, clutch means for operatively connecting the gear and screw for actuation of the latter, a head stock carried by the table, a drive motor carried by the table for actuation of the head stock, a shift lever coupled with the clutch to control the drive or stopping of the feed screw and thus the table movement, an oscillatable switch controlling member for regulating the starting and stopping of the motor, a rock arm associated with the switch, a second rock arm associated with the clutch lever and a link intermediate the rock arms having pivotal connection with one of said arms and a lost motion connection with the other of said arms comprising a slot in one of the parts and a pin in the other of the parts, moveable in the slot, whereby movement of the lever

operatively shifting the clutch will cause engagement of the end of the slot with the pin transmitting motion to the motor control member and causing actuation of the motor 5 while movement of the lever in the opposite direction will disengage the clutch without affecting the motor drive.

In testimony whereof I affix my signature.
FREDERICK S. HAAS.
